UNITED STATES PATENT OFFICE.

JOSEPH H. CHEEVER, OF SOMERVILLE, MASSACHUSETTS.

TELEPHONE-TRANSMITTER.

SPECIFICATION forming part of Letters Patent No. 292,203, dated January 22, 1884.

Application filed June 25, 1883. (No model.)

To all whom it may concern:

Be it known that I, JOSEPH H. CHEEVER, of Somerville, in the county of Middlesex and State of Massachusetts, have invented certain 5 Improvements in Telephone-Transmitters, of which the following is a specification.

My invention relates to telephone-transmitters of that class commonly known as "battery-transmitters," in which the variations in 10 strength of an electric current flowing through a primary coil of wire, and a variable contact caused by the vibrations of a diaphragm, induce in a neighboring coil of wire alternating currents of an undulatory character.

15 It consists in combining a microphone-transmitter with a coil-diaphragm transmitter, which latter instrument is described in an application of mine filed February 5, 1883. In this instrument alternating and undulatory 20 currents are induced in a secondary coil by the vibration of an electrically-charged coil of wire fastened to a diaphragm placed in proximity thereto.

25 In the present invention I have combined in one instrument the inductive effects of the variation in current-strength in a primary coil upon a secondary coil with the inductive effects of the bodily movement of a primary coil upon a secondary coil. By coupling these 30 inductive forces a considerable amount of current is caused to flow over the line-circuit, and loud effects are produced in the telephones connected therein, speech being transmitted with remarkable loudness and clearness.

35 The accompanying drawing, which forms a part of this specification, is a sectional view of the instrument in its simplest form of construction.

40 F is a suitable wooden frame, having a mouth-piece, M, inserted in the upright portion thereof. On the back of the upright portion is a recess or air-chamber, A. A diaphragm, D, preferably of iron, covers this recess, and is fastened at its edge by screws w to the frame F.

45 Attached by an insulating-cement to the diaphragm is a coil of insulated wire, R, composed of one or more layers, and of a diameter nearly equaling the diaphragm. This is shown in the drawing as being made of one layer of 50 wire. The inside terminal of this coil is soldered to the diaphragm shown at m. The other terminal is continued by wire 4 to a bat-

tery. In the center of the diaphragm is fastened a button of metal or carbon, e. This is in electrical connection with the diaphragm. 55

Facing the coil R is a secondary coil of insulated wire B, supported by a standard, N. This coil is made of a large number of convolutions of fine wire well insulated, and wound on a wooden spool. The terminals of 60 this coil are to be included in the line-circuit, shown as being connected with a hand-telephone, T. On the back of the secondary coil is fastened one of the primary electrodes, of which p is a carbon or metal button in loose 65 contact with the button e, and is fastened by a screw, a, to a spring, v, which spring is covered part of its length with rubber tubing, as is ordinarily done. The spring is secured to the spool by the screw s. 70

The operation of this telephone is as follows: On speaking into the mouth-piece the diaphragm and primary coil R are thrown into vibration. The primary coil is constantly charged with electricity, the current starting 75 from the battery Z passes over wire 3, through spring v and carbon-button p, through carbon e to diaphragm D, thence into the coil R at the internal contact m, and out by wire 4 to battery. With each movement of the diaphragm toward the coil B there is an increase 80 of current in the inducing-coil R due to an increase of pressure in the contact-carbons, and with each movement in the opposite direction there is a decrease of current in the 85 said coil. By this increment and decrement of current there are induced in the coil B alternating currents of electricity. Thus it will be noticed that we have currents induced in the coil B due to variation of the electric current flowing in the coil R, and also currents induced in the same coil due to the change in 90 position of the coil R. These induced currents are similar in character, and combine together, passing over the line-circuit 1 and 2, reproducing in the telephone T the sounds near or 95 the speech uttered in the mouth-piece M. This arrangement of the primary and secondary coils is advantageous, inasmuch that a greater amount of wire in the secondary coil may be 100 exposed to the direct influence of the primary coil.

I claim—

The combination, in a transmitting tele-

phone, of a diaphragm, a vibrating primary helix in a battery-circuit, and a variable resistance consisting of two points or buttons in loose contact with one another, also included 5 in the battery-circuit with a secondary helix adapted to form part of a closed telephone-circuit supported in inductive proximity to the primary helix, substantially as described.

In testimony whereof I have signed my name to this specification in the presence of two sub- 10 scribing witnesses this 22d day of June, 1883.

JOSEPH H. CHEEVER.
